(57) **CLAIM**

The ornamental design for a table lamp as shown and described.

DESCRIPTION

FIG. 1 is a front perspective view of a table lamp, showing my new design;

FIG. 2 is a rear perspective view thereof;

FIG. 3 is a bottom perspective view thereof;

FIG. 4 is a front elevational view thereof; the rear elevational view being a mirror image of FIG. 4;

FIG. 5 is a left elevational view thereof;

FIG. 6 is a right elevational view thereof;

FIG. 7 is a top plan view thereof;

FIG. 8 is a bottom plan view thereof;

FIG. 9 is an enlarged view of portion "9" shown in FIG.1;

FIG. 10 is an enlarged view of portion "10" shown in FIG.

2;

FIG. 11 is an enlarged view of portion "11" shown in FIG.

2;

FIG. 12 is an enlarged view of portion "12" shown in FIG.

3;

FIG. 13 is an enlarged view of portion "13" shown in FIG.

3;

FIG. 14 is an enlarged view of portion "14" shown in FIG.

3;

FIG. 15 is an enlarged view of portion "15" shown in FIG.

4;

FIG. 16 is an enlarged view of portion "16" shown in FIG.

6;

FIG. 17 is an enlarged view of portion "17" shown in FIG.

7;

FIG. 18 is an enlarged view of portion "18" shown in FIG.

8; and,

FIG. 19 is an enlarged view of portion "19" shown in FIG.

8.

The broken lines illustrate boundaries of the enlarged views

and form no part of the claimed design.

1 Claim, 17 Drawing Sheets
